UNITED STATES PATENT OFFICE.

JAMES DART, OF CHICAGO, ILLINOIS.

DOOR.

Application filed April 12, 1924. Serial No. 706,015.

To all whom it may concern:

Be it known that I, JAMES DART, a citizen of the United States, residing at Chicago, in the county of Cook and State of Illinois, have invented a certain new and useful Improvement in Doors, of which the following is a full, clear, concise, and exact description, reference being had to the accompanying drawings, forming a part of this specification.

My invention relates to doors and similar closures, and means for automatically opening the same actuated by the weight of the object passing therethrough.

Devices of this sort have been the subject of speculation to a considerable extent, but I am not aware that any such devices are in successful or general use. The vertical displacement available is necessarily quite small, and the movement of the door must be large, but a linkage multiplying the movement by the required ratio will so diminish the force that the door is very slow to open, and, in many instances, may have an initial friction sufficient to prevent opening at all. I believe this to be one of the primary difficulties involved, and one of the chief causes for the failure of devices previously proposed.

The primary object of the invention is to overcome the foregoing difficulty.

Further objects and advantages of the invention will become apparent as the description proceeds. In the accompanying drawings:

Fig. 1 is a side elevation and Fig. 2 an end elevation partly in section, of one embodiment of the invention;

Fig. 3 is a detail indicating an alternative arrangement for the carrying track;

Figs. 4 and 5 are side and end elevations similar to Figs. 1 and 2 of another type of construction;

Figs. 6 and 7 are detail sections on lines 6-6 and 7-7 of Fig. 4;

Fig. 8 is a section similar to Fig. 7 of a modified construction;

Fig. 9 is a side elevation of the parts shown in Fig. 8; and

Fig. 10 is a detail of an automatic stopping bumper.

In the embodiment of the invention selected for illustration in Figs. 1 and 2, the door sill 10 is suitably mounted for limited vertical movement. Door 12 is slidably mounted on a horizontal track 14 by suit-

able means such as wheels 16 and 18 riding on top of the track and wheel 20 riding below the track. Wheel 20 is nearer pulley 16 than 18. This facilitates the construction of Fig. 3, in which the end section of track 22 is pivoted at 24 and provided with a small counterweight 26 so that it will tip up when wheel 18 rides off it, and increase the vertical clearance at the center of the door opening.

The doors 12 illustrated are double doors, but as the construction on both sides of the door opening may be identical, only one side has been illustrated.

Rollers 28 lie under sill 10 on the ends of rocking levers 30 pivoted at 32. Links 34 connect with one end of rocking levers 36 pivoted at 38. The other ends of levers 36 connect with tension risers 40.

Posts 42 support fixed pivots 44, on which are magnifying levers 46, having their short ends pivoted to risers 40 and their long ends connected to links 48. Each link 48 actuates a bell crank lever 50, connected through link 52 with a back lever 54 actuating link 56 and link 58 pivoted at 60 to the door structure to pull the same back. Bell crank 62 connected to the pivot between links 56 and 58 carries a counterweight 64 to return the door to closed position. A suitable dashpot structure 62 may be connected to the system at any convenient or preferred point.

Gangplanks 64 connect the sill 10 with the surrounding foundation structure 66. It will be apparent that the downward force on sill 10 will increase uniformly as a weight passes across gangplanks 64 from zero when the weight first comes on the gangplanks to full value when the weight reaches the near edge of the sill. In the case of a four-wheeled vehicle, the width of the sill plus the length of the gangplank must be equal to the wheel base of the vehicle to maintain a constant load on sill 10 during passage of the vehicle through the door. If this is the case, the front wheels will reach the far edge of the sill, at the same instant that the rear wheels start across one gangplank. In practice, this need only be approximated, and the front wheel might traverse as much as one-third of the far gangplank before the rear wheels need start up the other gangplank. This is particularly true, because the wheel base usually increases with the weight of the vehicle. Thus, a

device designed to maintain full load throughout, with a standard vehicle of relatively light weight and short wheel base, would have the parts so proportioned that 5 the door would be held open at all times during passage of a heavier vehicle of longer wheel base, although while either set of wheels were directly on the sill 10, the load thereon would be in excess of that necessary 10 to hold the door open.

It will also be obvious that the total dimensions of the device measured between the remote ends of the gangplanks may be decreased by increasing the width of the 15 sill. Thus, by adding one foot to the width of the sill, one foot can be subtracted from the length of each gangplank, and the total over all dimensions decreased by one foot. It is obvious that this change in relative 20 dimensions may be continued until sill 10 becomes practically a wide scale platform, with short gangplanks to bridge the discontinuity between its edges and the surrounding foundation structure.

25 In Fig. 1, the parts are shown in the unloaded position with the door closed. It will be noted that lever 30 and link 34 are almost in alignment, and that lever 36 and riser 40 are also only slightly out of 30 alignment. This will result in a very large magnification of the force applied to roller 28. Of course, this implies also a different ratio of movement between parts 10 and 12. As the roller 28 moves down, lever 30 and 35 link 34 will move into a position more nearly at right angles to each other, and a similar movement out of relative alignment will occur between lever 36 and riser 40. This will increase the relative movement of door 12 40 with respect to sill 10, with a corresponding decrease in the effective force tending to open the door. Assume, for a practical example, that the vertical movement of the sill is a total of four inches, and the horizontal movement of the door must total four feet; at the beginning of the movement, the movement ratio between the parts will be much less than twelve to one, and at the end 45 of the movement much greater than twelve to one. Thus the toggle action of the linkage might be designed to make the initial ratio only two to one, which would increase rapidly during the opening movement of the door to perhaps thirty to one. This 50 not only assists in securing a quick opening of the door, by providing a large operating force at the beginning of movement when the inertia of the parts must be overcome, but in a large measure compensates for the varying force available for moving the parts as 55 the weight moves up gangplank 64.

In the embodiment illustrated in Figs. 4 to 6, inclusive, sill 10 may be substantially identical with the previous embodiment. I 60 have indicated equalizers comprising cross

shaft 68 carrying forked arms 70 engaging pins projecting from vertical plungers 72, to assist in controlling the movement of the sill and holding it horizontal at all times.

The toggles for producing the variations in effective leverage have been shifted, only one toggle being positioned before the magnifying lever, and the other being positioned after the same. Furthermore, the first toggle, is positioned close to the point of magnification of movement so that the heavy forces generated thereby need only be carried through a short distance. Thus riser 74 acting in tension to support the ends of sill 10 directly extends up parallel with post 76. Magnifying lever 78 is keyed on pintle 80, and extends down beside the door. With the parts of the relative dimensions indicated, considerably less than ninety degrees of rotation of arm 78 will open the door. Adjacent pintle 80 and for a short distance below the same post 76 is reinforced by a duplicate channel section 84, united therewith by plates 86 to form a box column. A fixed pintle 88 near the bottom 90 of the short box column carries rocker 90 pivoted at 92 to the upper end of riser 74 and at 94 to the lower end of short link 96 which actuates pintle 80 through crank arm 98. A turnbuckle 100 may be provided for adjusting the length of link 96.

It will be observed that pivots 88 and 94 are almost in line with link 96 when the door is closed. This forms the first toggle for increasing the initial leverage. Rotation of rocker 90 to open the door will not only bring pivots 88 and 94 into a line substantially at right angles to link 96, but pivot 92 will be fast approaching alignment of the crank arm represented by pivots 88 and 92 with tension link 74. It will be apparent that a variation in the effective leverage over a very wide range, and, to a certain extent, the shape of the curve representing such leverage at different positions of the door, may be controlled by the relative positioning of the three pivots 88, 94 and 92.

An extension link 102 is pivoted to the lower end of arm 78, and to a bracket 104 carried by door 12. It will be apparent that links 78 and 102 form a second toggle when the door is closed, to increase the effective leverage during the initial opening movement. As the force acting on bracket 104 can only be parallel to link 102, it will be observed that this large initial force not only pulls the door toward an open position, but will lift it upward, and tend to carry a substantial fraction of the weight of the door. This will relieve the load on guide wheels 16, 20 and 18, and materially diminish friction in the same.

Arm 78 is prolonged in the other direction at 106 and terminates in a counter-

weight 108. As the initial position of counterweight 108 is well below pintle 80, it will be apparent that the rotation of arm 78 will carry it up to a point where its effective leverage is materially greater than in the initial position. It will be obvious that this affords another opportunity for changing both the shape and dimensions of the curve of net effective force tending to open 10 the door for the different positions of the same.

Any suitable means for checking the movement of the door may be employed. I have illustrated a stationary dashpot 110 15 to cushion the opening movement. The closing movement may effectively be taken care of by a rubber bumper strip 112 along the edge of the door. As the inward movement of the two doors represents displacement of equal masses in opposite directions, they will not have any recoil with respect to the track or building when they meet.

However, to prevent excessive forces being developed by the sudden stopping of counterweight 108 through toggle links 102 and 78, I prefer to position an adjustable bumper 114 to engage said links at the end of the closing movement near their point of pivotal connection.

Referring now to Figs. 8, 9 and 10, I have illustrated a pivoted door 116 provided with a short crank arm 118 on its pintle 120. The eye 122 of rod 124 engages the end of crank arm 118. Post 126 supports a pintle 128 35 for a rocking lever 130 extended rearwardly to support counterweight 132 and at its forward end pivoted to arm 124 at 134. Tension member 136 is connected to an intermediate point on arm 130. It will be apparent that a downward pull on tension member 136 will rotate lever 130 in a clockwise direction, and that at the beginning of such movement levers 130 and 124 are nearly in line and form a toggle to magnify the 40 force applied to the door. Tension member 136 may be an extension of riser 74, or the upper end of link 96.

When the door opens by rotation, I may provide a bumper 138 supported on door 116 50 by parallelogram links 140. Spring 142 barely supports the weight of bumper 138 and link 140. In case some person should be standing near the door when it began to open and could not get out of the way, bumper 138 would be depressed to swing the toe of the lower parallelogram link into any one of a series of notches 144 to stop the opening movement of the door.

Without further elaboration, the foregoing will so fully explain the gist of my invention that others may, by applying current knowledge, readily adapt the same for use under various conditions of service. It will, for instance, be obvious that the variable effective leverage between sill and door

may be provided by means of cams instead of levers. These and many other alterations and modifications may readily be made by those skilled in the art without eliminating certain features which may properly be said to constitute the essential items of novelty involved, which items are intended to be defined and secured to me by the following claims:

I claim:

1. In a device of the class described, in combination, a wall having an opening, a vertically movable sill under said opening, gangplanks extending in opposite directions from said sill, fixed supports for the remote ends of said gangplanks, the proximate ends of said gangplanks resting on said sill, a slideable door for said opening, tension means supporting said sill, a fixed pivot, a rotatable member on said pivot rotated by said tension member, a second fixed pivot above the door, a crank arm on said pivot, a link pivoted to said rotatable member and crank arm, means for adjusting the effective length of said link, a long arm projecting down from said second pivot beside the door, and an extension pivotally connected to the door and said long arm, said extension and said adjustable link being both almost in alignment with the parts actuating them when the door is closed.

2. In a device of the class described, in combination, a wall having an opening, a vertically movable sill under said opening, gangplanks extending in opposite directions from said sill, fixed supports for the remote ends of said gangplanks, the proximate ends of said gangplanks resting on said sill, a slideable door for said opening, tension means supporting said sill, a fixed pivot, a rotatable member on said pivot rotated by said tension member, a second fixed pivot above the door, a crank arm on said pivot, a link pivoted to said rotatable member and crank arm, a long arm projecting down from said second pivot beside the door, and an extension pivotally connected to the door and said long arm, said extension and said adjustable link being both almost in alignment with the parts actuating them when the door is closed.

3. In a device of the class described, in combination, a wall having an opening, a vertically movable sill under said opening, gangplanks extending in opposite directions from said sill, fixed supports for the remote ends of said gangplanks, the proximate ends of said gangplanks resting on said sill, a slideable door for said opening, tension means supporting said sill, a fixed pivot, a rotatable member on said pivot rotated by said tension member, a second fixed pivot above the door, a crank arm on said pivot, a link pivoted to said rotatable member and crank arm, and connections between said

second fixed pivot and the door for opening the same, said link being almost in alignment with the part actuating it when the door is closed.

5. 4. In a device of the class described, in combination, a wall having an opening, a vertically movable sill under said opening, gangplanks extending in opposite directions from said sill, fixed supports for the remote 10 ends of said gangplanks, the proximate ends of said gangplanks resting on said sill, a slidable door for said opening, tension means supporting said sill, a fixed pivot, a rotatable member on said pivot rotated by said 15 tension member, a second fixed pivot above the door, a crank arm on said pivot, a link pivoted to said rotatable member and crank arm, a long arm projecting down from said second pivot beside the door, and an extension pivotally connected to the door and said long arm, said extension being almost 20 in alignment with the arm actuating it when the door is closed.

5. In a device of the class described, in

combination, a wall having an opening, a 25 movable horizontal sill under said opening, plungers secured to the bottom side of said sill for guiding the sill in a vertical direction, pins projecting from said plungers and forked arms engaging with said projecting pins to assist in constraining the movement of the sill and holding it horizontal at all times.

6. In a device of the class described, in combination, a wall having an opening, a 30 movable sill under said opening, a slidable door for said opening, a linkage connecting the sill and door for actuating the door by movement of the sill, said linkage comprising a magnifying lever, toggles between sill 35 and lever and between lever and door, and a counterweight angularly movable during opening of the door, said counterweight providing a variable closing force during 40 movement of the door.

In witness whereof, I hereunto subscribe my name this 10th day of April, 1924.

JAMES DART.
